COFFEE POT HANDLE

Richard I. Felver, Pittsburgh, Pa., assignor to
The Enterprise Aluminum Company, Massillon,
Ohio, a corporation of Ohio

Application December 1, 1953, Serial No. 27,853

Term of patent 14 years

(Cl. D44—26)

To all whom it may concern:

Be it known that I, Richard I. Felver, a citizen of the United States, residing at Pittsburgh, in the county of Allegheny and State of Pennsylvania, have invented a new, original, and ornamental Design for a Coffee Pot Handle, of which the following is a specification, reference being had to the accompanying drawing, forming a part hereof.

Fig. 1 is a side elevation of a coffee pot handle, showing my new design;

Fig. 2 is an elevation of the inner edge of the coffee pot handle shown in Fig. 1;

Fig. 3 is a top plan view of the coffee pot handle shown in Figs. 1 and 2;

Fig. 4 is a transverse, sectional view taken on the line 4—4 of Fig. 1; and

Fig. 5 is a transverse sectional view taken on the line 5—5 of Fig. 1.

I claim:

The ornamental design for a coffee pot handle, substantially as shown.

RICHARD I. FELVER.
